Upgraded eyebrow trimmer by Funstant, www.amazon.com, first available Jul. 2019 (Year: 2019)*

Primary Examiner — Jennifer Rivard

(74) Attorney, Agent, or Firm — Nitin Kaushik

(57) **CLAIM**

The ornamental design for an eyebrow trimmer, as shown and described.

DESCRIPTION

FIG. 1 is a perspective view of an eyebrow trimmer showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the eyebrow trimmer where a cover is sleeved on the eyebrow trimmer;

FIG. 10 is another perspective view thereof;

FIG. 11 is an enlarged top plan view of the eyebrow trimmer;

FIG. 12 is an enlarged view of portion 12 shown in FIG. 1;

and,

FIG. 13 is an enlarged view of portion 13 shown in FIG. 3. The broken lines in the drawings depict portions of the eyebrow trimmer that form no part of the claimed design.

1 Claim, 13 Drawing Sheets
